FRITZ KOCH, OF ST. PAUL, MINNESOTA

HOLLOW TILE FOR BUILDING PURPOSES

Application filed October 1, 1928. Serial No. 309,516.

In buildings where hollow tiles of the type in common use are exposed it has been found that the mortar between the tiles is a constant source of trouble. The mortar adjoining 5 outer surfaces and at the ends of the tiles is insecure and is often displaced into the hollow interior because the end surfaces are small in area. The joints are particularly weak where the outer surface of the structure 10 is pointed or where, for any reason, it is impractical to allow the mortar to protrude from the finished surface. These defects have made it impractical in the past to use hollow tile where it is exposed to wear or to the elements.

The object of this invention is to so form a hollow tile that a building constructed therefrom is strengthened and made more durable without substantially increasing its cost.

20 A further object is to provide a hollow tile which is adapted for use in the construction of an exterior or exposed portion of a building and to be pointed and re-pointed without re-laying. Other objects will appear and 25 be more fully pointed out in the following specification and claims.

Referring to the drawings which illustrate the best form of my device at present known to me, Figure 1 is an isometric view of a portion 30 of a wall constructed from my improved tile and partially in vertical section; Fig. 2 is a typical horizontal section through a joint taken on the line 2—2 of Fig. 1; Fig. 3 is a vertical section taken on the line 3—3 of Fig. 35 2 and Fig. 4 is a typical vertical section taken on the line 4—4 of Fig. 1.

My improved tiles, indicated by the numeral 5, are substantially rectangular, being 40 adapted to be laid in the usual manner and secured together by layers of mortar 6 between rows and mortar 7 applied to the adjoining ends of the individual tiles. Tubular openings 8 extend longitudinally through the 45 tiles so as to communicate one with another at the adjoining ends when the tiles are embodied in a wall or other building structure. Thus it will be seen that the end surfaces to 50 which the mortar 7 is applied are small in area and in the absence of special provision

for increasing the strength the joints formed by the mortar 7 are relatively weak.

I have found that these relatively weak joints are greatly strengthened and made durable by forming longitudinally extending 55 ribs 9 upon the interior surfaces and projecting into the tubular openings 8. The sides of these ribs 9 are preferably under-cut or of reentrant form so as to positively interlock with projections 10 upon the mortar 7 of the 60 end joints. In laying a wall or other structure with my improved tiles, the mason applies the mortar 6 and 7 in the usual manner and then while such mortar is in plastic state the 65 ends of an adjoining pair of tiles are pressed together, in accordance with the common practice. This causes the mortar to protrude longitudinally of the tiles, as indicated at 10 in Figs. 2, 3 and 4, within the openings 8 and also upon the exterior of the joints. The ends 70 of the ribs in one tile register with those in the adjacent tiles so that when the mortar sets a short, rigid body is left protruding at each side of the joint into the grooves between 75 ribs 9. Where it is desired to have the tiles exposed upon an interior or exterior surface 80 11 of the building the mortar joints 6 and 7 may be pointed up after removing the protruding portions of the mortar upon the said surface 11.

When the mortar of the projections 10 has set and hardened it has been found that the corresponding joints have ample strength by reason of my arrangement of the ribs 9 which positively interlock with the mortar between them. The ribs 9 also increase the end area of the tiles for adhesion to the mortar and this further adds to the strength of the joint and increases the amount of mortar which is caused to protrude in the locking grooves. It will be evident that forces tending to displace the mortar 7 inward from the front surface 11 are opposed by the projections 10 between the ribs 9 and outer walls 90 of the tile. Thus the joints may be pointed while the mortar is "green" without danger of displacing it into the hollow interior and where, after use and exposure to the elements, the joints require re-pointing, this 95 may be readily done without the tearing 100

down and re-laying of the tiles that has been necessary heretofore.

My invention is particularly adapted for use upon tiles of the type formed by the extruding process wherein a plastic mass of suitable clayey material is forced through a die to reduce it to tubular form, the soft tubular body being subsequently cut into the desired short sections and then dried and baked at a high temperature. The cost of such tiles is not substantially increased by the formation of the ribs 9 because they are produced by a simple change in the dies through which the plastic clay is extruded.

It will be understood that the interior ribs may be formed upon any or all walls of the tile, but I prefer to form them only upon the inner surface of the wall which is to be exposed or where increased strength at the joint is required.

Having described my invention what I claim is new and desire to protect by Letters Patent is:

1. A tile for building purposes comprising a rectangular body of hollow tubular shape having a wall adapted to be exposed on the exterior of a building structure and formed with longitudinally extending ribs upon the interior of said wall, the sides of said ribs being of reentrant form to positively interlock with mortar applied to the ends of the tile.

2. A tile for building purposes comprising a baked body of hollow tubular shape formed with a longitudinally disposed interior ribs extending to the ends thereof, the sides of said ribs being of reentrant form to positively interlock with mortar applied to the ends of the tile.

3. Hollow tiles adapted to be secured together end to end by mortar applied to the abutting ends, each comprising a body of tubular shape having a wall adapted to be exposed on the exterior of a building structure and formed with longitudinally extending ribs upon the interior of said wall, the ends of said ribs being arranged to register with the ribs in the adjacent tiles and the sides of said ribs being of reentrant form to positively interlock with mortar applied to the ends of the tile.

In testimony whereof, I have hereunto signed my name to this specification.

FRITZ KOCH.
